UNITED STATES PATENT OFFICE

ROLENZO NOBEL SHEARER, OF HOLLAND, MICHIGAN

FIRE ESCAPE

Application filed December 7, 1926. Serial No. 153,125.

The invention relates to means for escaping from burning buildings and has for its principal object the provision of a fire escape provided with a liquid brake to limit the speed of the shaft on which is wound alternately two bands or ribbons, the liquid brake comprising two cylinders on which are reciprocally mounted pistons connected with cranks on the shaft carrying the bands or ribbons, the two cylinders being connected by a pipe provided with a control valve and the pistons arranged to alternately move up and down, the fluid being contained in the cylinders and engaging the pistons to limit the reciprocal movement thereof, the speed of the shaft being regulated by the speed with which the liquid can move through the pipe connecting the cylinders, and the valve located in the pipe being adapted to regulate the orifice for the passage of the liquid to increase or decrease the speed of the shaft.

The invention will be described in detail hereinafter and will be found illustrated in the accompanying drawings, in which—

25 Figure 1 is a front view in elevation of the improved fire escape,

Figure 2, an end view, and

Figure 3, a transverse sectional view on a plane indicated by the line 3—3 of Figure 1.

30 In the drawings similar reference characters will be used to designate corresponding parts in the several views.

The improved fire escape comprises an angular bracket 1 that is adapted to be secured to the building in any suitable position and having depending journal members 2 on which is journaled a shaft 3 carrying two reels 4 on which are wound bands or tapes of any suitable material such for instance as steel or other fire-resisting material, and designated 5. One of the bands 5 is wound clockwise on the shaft and the other band is wound counter-clockwise, so that when the device is in use the bands may be alternately used for lowering persons to the ground, movement of one band downwardly winding the other band on the shaft to be again used when the lowering band has reached the ground and it in turn will be wound on the shaft by lowering the first

band. There are three journal members 2 arranged one between the reels 4 and the bands 5 and the other two on the outer side respectively of the reels 4 and bands 5 so that they serve to guide the bands in being wound on the reels as well as forming supports for the shaft 3.

Two cylinders designated 6, are secured to the bracket 1 and have pistons 7 arranged to reciprocate in said cylinders. L-shaped pitmen 8 connect cranks 9 on the ends of the shaft 3 with piston rods 10, said cranks being arranged so that one of the pistons 7 is descending while the other piston 7 is ascending. The cylinders 6 below the pistons 7 are filled with suitable fluid, such as oil of any required density, and the lower ends of the cylinders are connected by means of a pipe 11 to convey the oil from one cylinder to the other, and 12 is a regulating valve located in the pipe 11 to regulate the orifice for the passage of the oil so as to regulate the speed of the shaft 3 and the consequent descent of the person suspended on the descending band or ribbon 5.

The end of the band or ribbon 5 in each instance is provided with a loop 13 on which may be suspended a chair or other device for holding the person while descending from the building.

The operation of the device will be apparent from the drawings and description, and a further description is considered unnecessary. Attention is invited to the fact that the initial movement of the descending band or ribbon 5 will be its greatest movement, as the shaft 3 can only turn at a certain speed regulated by the valve 12 so that the speed of the person using the escape will be gradually reduced as the band is unwound from the reel 4 so that when he reaches the ground he will be going at the slowest speed of the band.

What is claimed is:—

A fire escape, comprising an angular bracket member, journal members secured thereto, a crank shaft journaled in said members, reels secured to said shaft between said journal members, flexible members arranged to wind alternately on said reels, a cylinder

supported by said brackets and arranged at each end of the crank shaft, a piston in each of said cylinders and operatively connected with the crank shaft, and a duct connecting said cylinders, the cylinders and duct containing a fluid completely filling the cylinders on one of the sides of the pistons.

In testimony whereof I affix my signature.
ROLENZO NOBEL SHEARER.
